UNITED STATES PATENT OFFICE

155,074

DESIGN FOR A COMBINATION WALLET AND
CIGARETTE CASE

Herbert Chase, New York, N. Y., assignor to Bernard Cahn Co. Inc., New York, N. Y., a corporation of New York

Application January 26, 1949, Serial No. 499

Term of patent 7 years

(Cl. D87—3)

To all whom it may concern:

Be it known that I, Herbert Chase, a citizen of the United States, residing in the city of New York, county of Queens, and State of New York, have invented a new, original, and ornamental Design for a Combination Wallet and Cigarette Case, of which the following is a specification, reference being had to the accompanying drawing, forming part thereof.

Fig. 1 is a perspective view of the combination wallet and cigarette case in a closed condition, the top flap being unbuttoned.

Fig. 2 is a perspective view of the said case in an open condition showing the outside of the wallet and the top flap in an open condition.

Fig. 3 is a perspective view of the said case, showing the inside of the same in an open condition, the top flap being in a closed condition.

Referring to Fig. 1, the bottom flap not shown except for the extension thereof with the female snap button thereon, is identical with the top flap, which is shown.

I claim:

The ornamental design for a combination wallet and cigarette case, substantially as shown and described.

HERBERT CHASE.
